UNITED STATES PATENT OFFICE.

ANNIE L. FAESTEL, OF MILWAUKEE, WISCONSIN.

TAILOR'S DRAFTING DEVICE.

SPECIFICATION forming part of Letters Patent No. 503,741, dated August 22, 1893.

Application filed April 10, 1893. Serial No. 469,696. (No model.)

To all whom it may concern:

Be it known that I, ANNIE L. FAESTEL, a citizen of the United States, and a resident of Milwaukee, in the county of Milwaukee, and 5 in the State of Wisconsin, have invented certain new and useful Improvements in Drafting Devices; and I do hereby declare that the following is a full, clear, and exact description thereof.

10 My invention has for its object to provide a dress-makers or tailors drafting-device combining a right-angle square and a series of independent curve-bars, the latter being designed as an aid to accurate drafting of the 15 neck, arms, sides and sleeves of a garment in accordance with a previously taken tape-line measurement; the said invention consisting in certain peculiarities of construction and combination of parts hereinafter specified 20 with reference to the accompanying drawing and subsequently claimed.

The drawing represents a plan view of a drafting device in accordance with my invention.

25 Referring by letter to the drawing A represents a two arm right-angle square shown as having both arms thereof provided with any suitable scale, such as inches and fractions thereof, and I prefer to provide at least one 30 of the arms with a folding section B in order to extend their length and yet economize space at such times as said square is not in use. Adjacent to their intersection, the arms of the square have their inner edges joined by a 35 curve bar C that may or may not be provided with a scale, arbitrary characters, marks or notches for the convenience of the person employing the device, this curve being designed for drafting the neck and arms of a garment 40 or the pattern representing the same. Joined to the arms of the square at their inner edges is another curve bar D, shown as provided with a scale, and this curve bar is designed for employment in drafting the sides of a garment 45 or a pattern representing the same. Still another curve bar E is joined to the arms of the square, and this latter curve bar is also shown

as provided with a scale, said curve bar being for employment in the drafting of the sleeves of a garment or a pattern representing the same.

By the employment of the several independent curve bars above specified the irregular lines of a garment or pattern for the same may be accurately determined, while 55 the regular lines of said garment or its pattern are obtained by the square. Hence by the combination of this square and said curve bars I provide a very convenient device for the use in the laying out of either male or female wearing apparel and insure an excellence of fit of such apparel.

Having thus described my invention, what I claim as new, and desire to secure by Letters Patent, is—

1. A drafting-device comprising a two arm right-angle square having a series of independent curve bars joining the inner edges of its arms, substantially as set forth.

2. A drafting-device comprising a two arm right-angle square having a series of independent curve bars joining the inner edges of its arms, and a folding continuation of one of said arms, substantially as set forth.

3. A drafting-device comprising a two arm right-angle square, a side form curve bar, and a sleeve curve bar, these curve bars being suitably scaled and joined at their extremities to the inner edges of the square-arms, substantially as set forth.

4. A drafting-device comprising a two-arm right-angle square, a neck and arm curve bar a side form curve bar and a sleeve curve bar, these curve bars being joined at their extremities to the inner edges of the square-arms, substantially as set forth.

In testimony that I claim the foregoing I have hereunto set my hand, at Milwaukee, in the county of Milwaukee and State of Wisconsin, in the presence of two witnesses.

ANNIE L. FAESTEL.

Witnesses:

N. E. OLIPHANT,
JNO. W. SEWENBERGER.
